CLAIM

The ornamental design for an orthopaedic grip, as shown and described.

DESCRIPTION

FIG. 1 is a perspective view of an orthopaedic grip showing our new design;

FIG. 2 an end elevational view thereof, taken from the end shown at the left in FIG. 1;

FIG. 3 is an opposite end elevational view thereof;

FIG. 4 is an enlarged side elevational view, showing the side opposite that shown in FIG. 1, the opposite side being a mirror image;

FIG. 5 is an enlarged top plan view of the design shown in FIG. 1; and,

FIG. 6 is an enlarged bottom plan view thereof.
